UNITED STATES PATENT OFFICE.

HAROLD D. FITZGERALD, OF DANVILLE, VIRGINIA.

RADIATOR.

Application filed June 2, 1923, Serial No. 643,038. Renewed September 15, 1926.

This invention relates to radiators such as are employed in connection with the heating systems, either steam, hot water or vapor, for dwellings or other buildings.

5 An object of the invention is to provide a radiator in which the usual feed and return connections at the ends of the radiator are dispensed with, thereby permitting the positioning of the radiator in a smaller space 10 than would ordinarily be required for the usual type of radiator having the same amount of radiation.

A further object of the invention is to provide a radiator which may be more readily 15 installed and is more sightly than radiators now in general use.

The invention consists, broadly, in providing a radiator section having a supporting leg or legs which serve as a passage or 20 passages for the heating medium, the leg being hollow so that its interior communicates with the interior of the radiator section, and also being adapted to be connected with the pipe line of the heating system. Both the 25 intake and outlet legs may be suitably disposed or located in the same section or at opposite ends of the radiator in different sections, as may be desired.

In the accompanying drawings there are 30 shown certain embodiments of the invention, and in the drawings:—

Fig. 1 is an end elevational view partly in section of a radiator having one of the improved sections therein,

35 Fig. 2 is a side elevational view,

Fig. 3 is a view of a modified construction showing the intake and outlet openings at opposite ends of the radiator, and

40 Figure 4 is a fragmentary end view looking toward the left of the modified construction shown in Figure 3.

Referring to the drawings for a more detailed description, 10 indicates a radiator section which, in the present instance, is located at the end of the radiator. The section is provided, at its bottom wall, with an intake opening 11 communicating with one of the vertical legs of the radiator 12, and a vertical passage in the upper end of which is positioned a valve seat 13 cooperating with a valve 14, which is operated by means of a manually controlled lever 15 on the exterior of the radiator. It will be noted that the valve is located within the radiator with only

the operating handle projecting therefrom, 55 and that the entire device is positioned so as not to project beyond the sides of the radiator. This permits the positioning of the radiator in a smaller space than is ordinarily possible when the usual type of valve is employed, which is spaced from the radiator, and by reason of the compact construction a larger number of radiator sections may be used in a limited space.

Generally, in radiators of this type, the 65 supply and return pipes are spaced from the radiator and are connected thereto by means of elbows and unions, which take up considerable space at each end of the radiator. To avoid this objection the section may be provided with a supporting leg 16, which is hollow and is provided with means, in the present instance a circumferential flange 17, adapted to engage the surface of the floor F or other suitable support around a pipe 70 opening 18. The interior of the leg 16 communicates with the interior of the radiator section and also with the supply pipe 19. For the purpose of connecting the leg to the supply pipe the leg is provided with an internally threaded countersunk end portion 20 which receives the threaded end of the supply pipe 19 projecting through the opening 18 in the floor. The upper end of the leg is beveled, as at 21, to enter a beveled 75 counter-sunk portion 22 adjacent the intake opening 11, and the leg is provided with a flange 23 which engages a flange upon a lock collar 24. The collar is internally threaded 80 to engage threads 25 upon the end of the radiator section. By means of the collar 24 the leg may be detachably secured to the radiator, and when installing the radiator it may be loosely secured thereto so that it is 85 rotatable for the purpose of fixedly connecting the same to the intake pipe 19. The leg may be connected to the radiator by turning the collar a few times upon co-operating threads of the radiator, whereby the leg is 90 rotatably connected to the radiator and may be engaged by a wrench or other suitable tool for the purpose of rotating and threading the same upon the end of the supply pipe 19.

After the pipe and leg are securely connected the collar 24 may be rotated to complete 100 the joining of the leg with the radiator section.

The section 12, shown in Fig. 1, is also

provided with an outlet opening 26 communicating with the interior of a supporting leg 27, which is provided with the circumferential floor engaging flange 17 and is connected to the return pipe 28 in the same manner as the leg 16. Obviously, as is shown in Fig. 3, the outlet connection and supporting leg may be positioned in a distinct section 29 at the opposite end of the radiator. 10 The invention also contemplates the provision of the usual thermostatic valve, which is normally open to permit the passage of fluid, such as water in a steam system, but which will close when steam comes in contact therewith. The invention seeks to position this valve within the radiator so that the same is inconspicuous and will not project beyond the end or sides of the radiator. Referring to Fig. 1, there is positioned in 15 the outlet opening 26 a valve casing 30 having a stem portion 31, which is threaded to engage threads in the opening 26 and is thereby secured in position. The casing has an internal bore 32 communicating with the 20 interior of the supporting leg 27, and through the seat 33 with the interior of the radiator. The upper end of the casing has a plurality of openings 34 forming a cage for a valve 35, which is of the usual thermostatic type, such as a bellows containing fluid that expands and causes the valve head 36 to engage the seat 30 when steam strikes it. The portion 30' of the valve casing on the exterior of the radiator is shaped to correspond, generally, to the shape of the lower end of the radiator section surrounding the inlet opening, and is threaded so that it may be engaged by a collar 24', which serves to 25 secure the supporting leg to the radiator section. 40

It will be noted that upon the interior of the section the wall of the valve casing below the seat, or for a considerable distance above the surface of the radiator section wall surrounding the opening, is imperforate, thereby providing a sediment pocket P surrounding the valve casing. This pocket serves to collect foreign matter and other sediment which falls to the lower end of the 45 radiator and adjacent the inlet opening, and it may be readily cleaned by disconnecting the radiator leg 27 and removing the valve casing, which is accomplished by engaging the portion of the casing upon the exterior 50 of the radiator with a wrench, or other tool. 55

It will be understood, of course, that although, in Fig. 1, both the intake, or supply opening, and the return opening, with the thermostatic valve, are positioned in the 60 same radiator section they may be suitably located or positioned singly in distinct sections, as shown in Fig. 3 so as separately to support the radiator adjacent its opposite ends. In all instances the thermostatic valve 65 will, preferably, be positioned in the outlet

or return opening. Obviously, the supporting leg construction is applicable to wall supported radiators, in which the leg will assist the usual hangers in supporting the radiator. 70

I claim:

1. A hollow supporting leg, comprising a circumferential flange adapted to engage the surface of a floor or other support around a pipe opening and to cover the opening, means for connecting the leg to a pipe at said opening, and means for connecting said leg to a radiator. 75

2. A hollow supporting leg open at both ends, comprising a circumferential flange adapted to engage the surface of a floor or other support around the pipe opening and to cover the opening, and a flanged collar for clamping said leg to a radiator. 80

3. A radiator section having an opening 85 at its bottom, a hollow supporting leg on said radiator section the interior of the leg communicating with the interior of the radiator through said opening, means for detachably securing the leg to the radiator, 90 means on said leg adapted to engage the surface of a floor or other support surrounding a pipe line opening, and means for connecting the leg to a pipe in said opening. 95

4. A radiator section having an opening adjacent its bottom, a hollow supporting leg on said radiator section, the interior of the leg communicating with the interior of the radiator through said opening, means on said leg adapted to engage the surface of a floor or other support around a pipe line 100 opening, and means for connecting the leg to a pipe in said opening.

5. The combination with a radiator section having an opening adjacent its bottom 105 and a threaded extension around said opening, of a hollow supporting leg having a flange adapted to engage the surface of the floor or other support around a pipe line opening, means for connecting said leg with a pipe in said opening, and freely rotatable means on said leg for engaging the threads on said radiator section and connecting the leg thereto. 110

6. The combination with a radiator section having an opening adjacent its bottom and a threaded extension around said opening, of a hollow supporting leg having a flange adapted to engage the surface of the floor or other support around a pipe line 115 opening, said leg making a substantially butt joint with the radiator section at said opening, means for connecting said leg with a pipe in said opening, and freely rotatable means on said leg for engaging the threads on said radiator section and connecting the leg thereto. 120

7. A hollow supporting leg for a radiator open at both ends and having a circumferential flange adapted to engage the sur- 125 130

face of the floor or other support around a pipe opening and to cover the opening, and a freely rotatable flanged collar on said leg for clamping together the leg and the radiator section.

8. A hollow radiator supporting leg, comprising a relatively short tubular leg member, outwardly extending means on said leg member adapted to engage the surface of a floor or other support around a pipe opening, means for connecting the leg to a pipe at said opening, and means for connecting the leg to a radiator section.

9. The combination with a radiator section having an opening adjacent its bottom, of a hollow supporting leg having outwardly extending means adapted to engage the surface of the floor or other support around the pipe line opening, means for connecting said leg with a pipe at said pipe line opening, said radiator section resting directly upon the leg and the latter receiving the weight of the section at its bottom opening, and means for connecting said section and the leg.

10. The combination with a radiator section, having an opening adjacent its bottom, of a hollow supporting leg having outwardly extending means adapted to engage the surface of the floor or other support around the pipe line opening, means for connecting said leg with a pipe at said pipe line opening, said radiator section resting directly upon the leg and the latter receiving the weight of the section at its bottom opening, and freely rotatable means for connecting said section and the leg.

11. The combination with a radiator section, having an opening adjacent its bottom, of a hollow supporting leg having means to engage the surface of a floor or other support around a pipe line opening, said leg making a joint with the radiator section at said bottom opening and carrying the weight of the section at the joint, means for connecting said leg with a pipe at said pipe line opening, and means for connecting the leg and the radiator section.

12. A radiator, comprising in combination, a series of connected heat radiating sections, a threaded nipple extending downwardly from one of the sections, a hollow leg adapted to be secured to said nipple and having an outwardly flaring base constructed to rest firmly on the floor to support the radiator and provided with a conduit for conducting fluid from a supply pipe to the radiator through the radiator supporting leg.

13. A radiator, comprising in combination, a series of connected heat radiating sections one of which is provided with a vertical inlet opening at its lower end, a hollow leg removably secured to said section and having an outwardly flaring base con-

structed to rest firmly on the floor to support the radiator and provided with a conduit for conducting fluid from a supply pipe to the radiator through the radiator supporting leg.

14. A radiator, comprising in combination, a series of connected heat radiating sections one of which is provided with an inlet opening in its lower end, a hollow radiator supporting leg having a spreading base constructed to rest firmly on the floor to support the radiator and provided with a conduit for conducting fluid to the radiator, means for securing the leg to a fluid supply pipe extending upwardly from the floor, and means for securing the leg to the radiator section after the leg has been secured to said pipe.

15. A radiator, comprising in combination, a series of connected heat radiating sections, a hollow leg for supporting the radiator sections and for supplying heating fluid thereto, comprising a hollow base constructed to rest upon the floor and adapted to be secured to a supply pipe, a hollow nipple extending downwardly from one of the radiator sections, and a connection between the hollow base and nipple including a union nut.

16. A radiator, comprising in combination, a series of connected heat radiating sections, means for supporting the radiator comprising hollow legs extending downwardly from the end sections and provided with flaring base portions adapted to rest upon the floor, each leg having formed therein a fluid-tight conduit communicating with the interior of the radiator, means removably securing the legs to their respective sections, and means for connecting one hollow leg to a supply pipe and the other to a return pipe.

17. A radiator comprising in combination, a series of connected heat radiating sections, one of said sections being divided by an interior wall to form a separate conduit at one side of the section, a vertically disposed inlet port formed at the lower end of said section and leading into said separate conduit, a valve for controlling the passage of fluid from said conduit into the remaining portion of the section, a hollow leg forming a pedestal for supporting said section from the floor and provided with a fluid passage communicating with said port, and means for connecting the leg to a source of fluid supply.

18. A radiator comprising a series of connected heat radiating sections, a nipple extending downwardly from each of two separate sections adjacent the ends of the radiator, a single hollow leg secured to each of said sections at said nipple and having an outwardly flaring base constructed to rest firmly on a floor or the like, suitably ar-

ranged to support the radiator adjacent its ends and providing it with a fluid conducting conduit, and means associated with each leg for connection of the same with a pipe line.

19. A radiator comprising in combination, a series of connected heating radiating sections and means for supporting the radiator adjacent its ends comprising a single hollow leg adjacent each end and provided with a flaring base adapted to rest upon a floor or the like and suitably disposed to support the

radiator, each leg having formed therein a fluid-tight conduit communicating with the interior of its respective radiator section, means for securing the legs to their respective sections, and means for connecting each leg to a pipe line through an opening in the floor or support beneath said flaring base.

20. In testimony whereof I have hereunto set my hand.

HAROLD D. FITZGERALD.
